**CLOSURE FASTENING DEVICE FOR A PURSE,
HANDBAG, OR SIMILAR ITEM**

Georg Reitzel, Altenmittlau, Kreis Gelnhausen, Germany, assignor of one-half to Drescher & Kiefer, Altenmittlau, Kreis Gelnhausen, Germany, a German firm, and one-half to Randolph-Rand Corporation, New York, N.Y., a corporation of New York

Filed Feb. 18, 1965, Ser. No. 433,652
6 Claims. (Cl. 292—87)

The present invention relates to a closure latching device for a lady's purse, handbag or similar accessory, and more particularly to a closure latching device of this kind the closure members of which are retained in the closed position by spring action and are released by overcoming the spring action.

It is an object of the invention to provide a novel and improved closure latching device of the general kind above referred to the entire mechanism of which is located within the lateral outline of the frame of the purse or similar item. This has the advantage that the closure latching device is not likely to become entangled with other items, such as handkerchiefs, etc., carried in a handbag in addition to a purse. Such entanglement may cause damage to the respective items and accidental opening of the closure device. Another advantage of the closure device according to the invention is that it affords increased protection against pickpockets, since a clandestine opening of the device is more difficult than the opening of a conventional closure device having parts protruding laterally from the frame of the purse, handbag or similar item.

A more specific object of the invention is to provide a novel and improved closure device of the general kind above referred to which is self-closing when the closure members of the device are pressed against each other and which is released by laterally tilting a closure latching member upwardly protruding from the frame.

Another more specific object of the invention is to provide a novel and improved closure latching device of the general kind above referred to which is simple and sturdy in design, convenient in operation and inexpensive to manufacture, and which permits a highly ornamental configuration without adversely affecting the closing action and the safety of the device.

Other and further objects, features and advantages of the invention will be pointed out hereinafter and set forth in the appended claims constituting part of the application.

In the accompanying drawing a preferred embodiment of the invention is shown by way of illustration, and not by way of limitation.

In the drawing:

FIG. 1 is a perspective view of a purse with a closure device according to the invention;

FIG. 2 is a fragmentary sectional view taken on line 2—2 of FIG. 1 or FIG. 3 on an enlarged scale;

FIG. 3 is a sectional view taken on line 3—3 of FIG. 2;

FIG. 4 is a fragmentary plan view of one frame portion of the closure device;

FIG. 5 is a fragmentary view of another frame portion of the closure device;

FIG. 6 is a side view of a component of the mechanism of the closure device;

FIG. 7 is an end view of the component of FIG. 6;

FIG. 8 is a plan view of the component of FIG. 6;

FIG. 9 is a side view of another component of the mechanism;

FIG. 10 is a right-hand end view of the component of FIG. 9;

2

FIG. 11 is an elevational side view of still another component of the mechanism;

FIG. 12 is an end view of the component of FIG. 11;

FIG. 13 is a top view of the component of FIG. 11, and

FIG. 14 is an end view of the closure device showing the same in its open position.

Referring now to the figures in detail, and first to FIG. 1, the purse shown in the figure comprises a frame consisting substantially of two generally U-shaped frame members 10 and 11. The two frame members which may be made of any suitable material, such as metal or plastic, are hinged together at the free ends of their side arms by any suitable means, such as rivets or screws 12. The frame members, particularly the base portions 10a and 11a thereof, may have the generally U-shaped cross section shown in FIG. 2, whereby the outer branch may be somewhat longer than the inner branch. As is evident, the two base portions of the frame members may be pivoted from the side-by-side position of FIG. 1, which constitutes the closed position of the device, into a spread-apart open position to provide access to the interior of the purse. The purse proper may be made of any pliable material suitable for the purpose, such as fabric or leather, and is secured to the frame in a conventional manner to form a pocket 13. The structure of the purse itself does not constitute part of the invention and hence is not described in detail. As previously pointed out, the invention is concerned with the closure latching device 15, including the portions of the frame which constitute part of the closure device. The closure device will now be described more in detail.

The closure latching device comprises a catch nose 20 upwardly protruding from the base portion 10a of frame member 10. The nose may be raised out of the material of the frame member, as shown in FIG. 2, but may also be a separate element suitably secured to the top side of frame member 10a. In this connection it should be mentioned that the frame members need not have the exemplified U shape, but may be in the form of simple bars, or may have any other suitable shape.

The frame member 11a mounts a generally sleeve-shaped holder 21 suitably secured to the frame member, for instance, by extending the holder through an opening 22 in the top side of member 11a and soldering or brazing a branch 21a of the holder to the inside wall of frame member 11. The holder may also be secured directly to the top surface of frame member 11a in a conventional and suitable fashion.

The closure latching device further comprises a locking member 25 in the form of a generally rectangular box. The box has a flat bottom plate 25a. The box is open opposite the bottom, and one of the side walls may be left open, as is shown in FIGS. 6, 7 and 8, to facilitate mounting of the box and the components therein, as will be more fully explained hereinafter. The plate 25a includes two elongated slots 26 and 27 which extend parallel to frame portions 10a and 11a.

Holder 21 extends through slot 26, and the protruding portion of the holder serves to accommodate and retain a locking member 30. As can best be seen in FIG. 9, the locking member may be of generally U-shaped configuration. Branch 30a of the member 30 may be flattened and is fitted into the protruding portion of holder 21. The other branch, 30b, forms a springy arm which is biased downwardly in reference to the protruding holder portion and also in reference to plate 25a. Accordingly, the springy arm will tend to tilt plate 25a in counterclockwise direction as seen in FIG. 2 about the apex or base portion of frame member 11 as a fulcrum. Two noses 32 and 33 on frame member 11a limit the tilting of the box in counterclockwise direction to the approx-

imately horizontal position shown in FIG. 2. Instead of the specific configuration of locking member 30 as shown in FIGS. 9 and 10, the locking member may also be in the form of a simple round wire. It is essential merely that the locking member be retained by the holder and have a downwardly biased locking portion similar to locking arm 30b.

Catch nose 20 is positioned to be received in slot 27 of plate 25a and to protrude through the slot when the two frame members 10 and 11 are placed in the side-by-side position shown in FIGS. 1, 2 and 3. The springiness of arm 30b permits entry of catch nose 20 into the position illustrated in FIG. 2 by allowing a slight tilting of box 25 in the clockwise direction as seen in FIG. 2. Arm 30b is so positioned and biased that it will engage behind catch nose 20 when the two frame members 10a and 11a are in the illustrated side-by-side position, thereby locking the two frame members together, as desired.

To release nose 20 from the locking position of FIG. 2, plate 25a is slightly tilted in clockwise direction against the action of springy arm 30b of locking member 30.

Base plate 25a is secured in a cap 40, partly for ornamental reasons, to conceal the closure mechanism of the device, and partly to protect the locking member 30 and the protruding portion of holder 21. Cap 40 may be made of polished metal and be further adorned, for instance, by inserting a colored piece of glass. The cap preferably has a transverse frustoconical cross section, as is clearly shown in the figures. It is disposed lengthwise of frame member portions 10a and 11a. The maximum width of the cap is shown as being less than the combined transverse widths of frame member portions 10a and 11a to avoid overhanging of the closure latching device over the frame of the purse.

The cap is open on its wide parallel side, and plate 25a is secured to the open side of the cap by any suitable means. As is evident from the foregoing description, a flat plate 25a is functionally sufficient, but it is preferable to provide the plate as the base of a generally rectangular box, as previously stated. Such boxlike structure lends greater strength to the closure device and facilitates the mounting of plate 25a in cap 40. The inner walls of the cap include a generally rectangular portion 40a, and the side walls 25b of holder 25 are suitably secured, for instance by force fitting, in the rectangular wall portions of cap 40.

Reverting to FIG. 1, this figure shows the finished purse in its closed position. FIG. 14 shows the closure device released by simply tilting cap 40 from the position of FIG. 1 into the position of FIG. 14. As is shown in the latter figure, nose 20 is clear of slot 27 in plate 25a and arm 30b, and the two U-shaped frame members 10 and 11 may now be spread apart to provide access to the purse. To close the purse, the two frame members are simply pressed against each other, and the resulting pressure exerted by nose 20 upon plate 25a will force the cap toward the position of FIG. 14 until finally nose 20 snaps into slot 27 and against arm 30b, whereupon the cap returns into the position of FIG. 1.

While the invention has been described in detail with respect to a certain now preferred example and embodiment of the invention, it will be understood by those skilled in the art, after understanding the invention, that various changes and modifications may be made without departing from the spirit and scope of the invention, and it is intended, therefore, to cover all such changes and modifications in the appended claims.

What is claimed is:

1. A closure latching device for a purse, handbag or similar item, said device comprising a frame including two bars movable between a side-by-side closure position and a spaced-apart open position, a catch nose upwardly protruding from one of said bars, a holder secured to the other bar upwardly protruding therefrom, a locking member secured to said holder and including a springy

arm biased into locking engagement with said nose when the two bars are in said closing position, and a locking plate including two slots, said holder protruding through one of said slots and said springy arm being located on the side of the plate opposite the respective bar, said holder and said locking member retaining the plate on the respective bar slightly tiltable in reference thereto, said nose protruding through the other slot in said plate in the closing position of the bars for engagement of the nose by said springy arm, tilting of the plate against the bias of the springy arm disengaging the nose from the arm and the plate, thereby releasing the closure latching device.

2. A closure latching device for a purse, handbag or similar item, said device comprising a frame including two bars movable between a side-by-side closure position and a spaced-apart open position, a catch nose upwardly protruding from one of said bars, a holder secured to the other bar upwardly protruding therefrom, a locking member secured to said holder and including a downwardly biased springy arm on the side of the holder facing said nose, said springy arm engaging behind said nose in reference to said holder when the two bars are in said closing position, a locking plate including two slots, said holder protruding through one of said slots and said springy arm being located on the side of the plate opposite the respective bar, said holder and said locking member retaining the plate on the respective bar slightly tiltable in reference thereto, said nose protruding through the other slot in said plate in the closing position of the bars for engagement of the nose by said springy arm, tilting of the plate against the bias of the springy arm disengaging the nose from the arm and the plate, thereby releasing the closure latching device and a cap secured to said plate and covering the protruding holder portion and the locking member, said cap being tiltable in unison with the plate.

3. A closure latching device for a purse, handbag or similar item, said device comprising a frame including two substantially parallel closure bars movable between a side-by-side closure position and a spaced-apart open position, a catch nose upwardly protruding from one of said bars, a holder secured to the other bar upwardly protruding therefrom, a locking member secured to said holder and including a downwardly biased springy arm on the side of the holder facing said nose, said springy arm engaging behind said nose in reference to said holder when the two bars are in said closing position, a substantially rectangular locking plate extending lengthwise parallel to said bars and including two slots, the width of said plate being within the combined width of said bars, said holder protruding through one of said slots and said springy arm being located on the side of the plate opposite the respective bar, said holder and said locking member retaining the plate on the respective bar slightly tiltable in reference thereto, said nose protruding through the other slot in said plate in the closing position of the bars for engagement of the nose by said springy arm, tilting of the plate against the bias of the springy arm disengaging the nose from the arm and the plate, thereby releasing the closure latching device, and an elongated cap secured to said plate and covering the protruding holder portion and the locking member, the width of said cap being within the combined width of said bars, said cap being tiltable in unison with the plate.

4. A closure device according to claim 3, wherein said cap has a substantially frustoconical transverse cross section, the wide parallel side of the cap being open, said plate being secured to the cap at said open side thereof to form a closed base side for the cap.

5. A closure device according to claim 4, wherein said plate constitutes the base of a substantially rectangular box, and wherein the inner walls of said cap include wall portions defining a substantially rectangular receptacle, said box being secured in said receptacle.

6. A closure latching device for a purse, handbag or

similar item, said device comprising a frame including two closure bars movable between a side-by-side closure position and a spaced-apart open position, a catch nose upwardly protruding from one of said bars, a holder secured to the other bar upwardly protruding therefrom, a generally U-shaped springy locking member, one arm of said member being secured to said holder and the other being downwardly biased to engage said nose in locking engagement when the two bars are in said closing position, a locking plate extending parallel to said bars and including two slots, said holder protruding through one of said slots and said springy arm being located on the side of the plate opposite the respective bar, said holder and said locking member retaining the plate on the respective bar slightly tilttable in reference thereto, said nose protruding through the other slot in said plate in the closing position of the bars for engagement of the nose by said springy arm, tilting of the plate

against the bias of the locking member disengaging the nose from the arm and the plate, thereby releasing the closure latching device, and a cap secured to said plate and covering the protruding holder portion and the locking member, said cap being tilttable in unison with the plate.
